UNITED STATES PATENT OFFICE.

ADOLPH A. THOMAS, OF NEW YORK, N. Y., ASSIGNOR TO BRANDES LABORATORIES, INC., OF NEWARK, NEW JERSEY, A CORPORATION OF NEW JERSEY.

LOUD-SPEAKING TELEPHONE RECEIVER.

Original application filed December 14, 1923, Serial No. 680,597. Divided and this application filed May 11, 1925. Serial No. 29,472.

My invention relates to telephone instruments, and its main object is to provide a loudspeaking receiver particularly adapted for use in radio reception, although not limited to this field.

My invention comprises improved means for mounting the operative parts of a telephone loudspeaker in a readily accessible position within an outer casing or housing, which is rigidly mounted on a stand or base and to which a horn is connected. To the lower end of the casing within the base is secured a cap member which carries suitable magnetic mechanism adapted to operate an acoustic diaphragm within the upper casing. As a result of this novel construction and arrangement, the parts of the instrument are readily assembled and taken apart, when occasion requires.

In the construction which I prefer at the present time, the outer casing is supported on and connected to the base by a snug firm fit, so that the base may be removed without the use of special tools, as when it is desired to connect the mechanism with a phonograph horn or other fixed amplifier.

The foregoing and other objects and advantages of my invention will become clear from a detailed description of the accompanying drawings, which illustrate a preferred embodiment of my invention. In these drawings—

Fig. 1 is a transverse cross-section on line 1—1 of Fig. 2, showing a loudspeaking telephone receiver constructed in accordance with my invention;

Fig. 2 is a top plan view in section, approximately on the broken line 2—2 of Fig. 1; and

Fig. 3 is a detached perspective view of the casting or cap member which directly supports the magnetic mechanism and, in this particular instance, also the diaphragm.

An outer casing or housing indicated as a whole by K is supported on a base or stand T of suitable construction and design. The housing K, which may be cast or molded as a single piece of any suitable material (such as bakelite, aluminum, etc.), consists of a closed upper section 1 and an open lower section 2. The upper section 1 is provided with an integral neck 3 adapted to receive the inner end 4 of a suitable amplifying horn. For this purpose, the neck 3 may be made slightly cone-shaped, so as to provide a tight fit for

the horn. Between its upper and lower sections, the housing K is provided with an outwardly projecting annular flange 5 arranged to engage an annular shoulder or flange 6 which forms the top edge of base T. The housing K has a cylindrical portion 7 adapted to fit snugly and firmly into the opening 8 in the base or stand T, while the annular flange 5 of the casing rests on the top of the base. The frictional and positive securing means thus formed by the engaging surfaces of base T and housing K is sufficient to hold the housing securely on its supporting base, and no separate fastening devices are necessary in this preferred construction. To remove the casing K and all parts carried thereby, it is only necessary to separate it from the base, which is easily done without the use of tools. The instrument may be used without the stand T, as when it is desired to connect it with a phonograph horn in a cabinet. In that case, the neck or extension 3 is shaped to fit over the outer end of the tone arm or whatever acoustic connection with the horn may be used.

To the lower section 2 of casing K is secured a casting indicated as a whole by B, as best shown in Fig. 3. This casting, which may be called a second housing, in this instance comprises a circular base section 9, a ring 10, and connecting posts 11. If desired, these parts may be made separate and rigidly secured together, but it is preferable to mold or cast them in a single rigid piece out of a suitable non-magnetic material, such as aluminum, bakelite, and the like. So it will be understood that when I refer to the part B as a casting, I use the term merely for convenience.

On the base section 9 of the supporting member B is mounted any practical form of magnetic mechanism suitable for operating an acoustic diaphragm. Merely by way of example, I have shown a pair of permanent magnets fixed on the base section 9 by suitable fastening devices, such as screws 14. These magnets are arranged with their like poles opposite, as indicated in Fig. 2. To the poles of magnet 12 are secured pole pieces 15 and 16, and to the magnet 13 are secured similar pole pieces 17 and 18. The two pairs of pole pieces extend toward each other as shown in Fig. 2, being separated by an air gap 19. The two magnets constitute in effect

a single magnet with a bifurcated north pole 15-17 and a bifurcated south pole 16-18 (or vice versa). Although I have referred to the magnets 12 and 13 as permanent magnets, they may obviously be in the form of electromagnets.

The pole pieces 15-17 and 16-18 are connected by iron cores 20 on which are mounted coils 21 adapted to be connected in a suitable telephone circuit in which the current varies in accordance with sound waves intended to be reproduced by the receiver. These coils are connected in series and thus in effect constitute a single coil, which I may conveniently 15 call the telephone coil.

Between the tips or free ends of pole pieces 15-17 and 16-18 is mounted an armature A, which may simply be a short flat bar of iron of the right size, depending upon the relative 20 arrangement and size of the pole pieces. The armature is operatively supported in any practical way. In the drawings I have shown a U-shaped bracket 22 between the arms of which is pivoted a stud 23 constructed to 25 hold the armature A. In Fig. 1, the stud 23 is shown slotted to receive the armature and support the same rigidly at the center. The bracket 22 is firmly mounted on the base section 9 of housing B in any suitable way, as 30 by means of screws or bolts 23. Any other practical mounting for the armature may be used.

The lower end of casing K is screw-threaded to receive the screw-threaded shoulder 24 35 of casing B, which thus forms a cap or housing for the lower end of the casing. To permit easy manipulation of housing B in screwing it into or out of the casing, the base section 9 may be formed with a slightly projecting flange or rib 25, which is easily 40 grasped by the fingers.

On the ring 10 of member B is mounted an acoustic diaphragm D of proper design and material. There are many kinds and 45 styles of diaphragms on the market suitable for this purpose. The most common material of which these diaphragms are made is mica, which is moisture-proof and gives a strong reproduction. Some people prefer a diaphragm of wood, especially maple, which 50 gives a more pleasing reproduction than mica, though perhaps not as strong.

Diaphragm D is held in place on the ring 10 in any practical way. In the illustrative 55 embodiment shown in the drawings, the supporting ring 10 has an inwardly projecting shoulder or flange 26 and a screw-threaded wall 27. The diaphragm is clamped firmly in position by a screw-threaded ring 28. It is preferable to clamp the diaphragm between a pair of washers 29 of felt, leather, 60 rubber, or other sound-absorbing material. When the housing or cap member B is fully 65 screwed into the casing K, the top of ring 10 may rest against a shoulder formed inside the

casing, as shown in Fig. 1, but this is not essential when the diaphragm is held clamped on ring 10 independently of the casing, as by the screw-threaded ring 28.

To the ring 10 is fixed a bracket 30 having 70 a pair of spaced lugs 31, between which is pivoted at 32 a lever indicated as a whole by L. This lever is in the form of a bell-crank comprising a long arm 33 and a short arm 34. The free end of the long arm 33 is rigidly secured to the center of diaphragm D, as indicated at 35 in Fig. 1. The short arm 34 of lever L is provided with a lateral extension 36, which may be an integral part of the lever. The free end of the extension 36 is connected 80 to the armature A by a rod or stiff wire 37, or any other practical means. The point at which the rod 37 is connected to the armature depends upon the amplifying ratio which it is desired to secure between the vibratory 85 movements of the armature and the vibratory movements of the diaphragm D. By properly calculating the distance between the center of the armature and the point of connection of the rod or wire 37, and by further calculating the lengths of the arms 33 and 34 of lever L, any desired leverage between the armature and the diaphragm can be secured. These 90 calculations are well within the skill of the man conversant with this art. 95

The operation of my new telephone receiver will be clear to anyone skilled in the art and I need not, therefore, go into any details on this point. It is enough to say that normally the armature A is held in a neutral or balanced position between the tips of the pole pieces, as shown in Fig. 2. When a variable current passes through the coil or coils 21, the normal magnetic balance of the armature is disturbed by the resultant magnetic 105 effect of the coils and the armature vibrates in a manner well understood. These vibrations are in accordance with the current variations in the coil and are transmitted in increased ratio through the connections previously described. In this way, the vibrations of the armature are repeated by the diaphragm in magnified movements, so that the sound produced by the diaphragm may be heard at a distance. 110

The specific form of magnet construction and operative connections for the acoustic diaphragm are here set forth merely by way of example and not as a restriction or limitation. It is obvious that, in the broader aspect 120 of my invention, any suitable magnetic mechanism may be mounted on the cap member or housing B. In the preferred embodiment herein described, the closed casing consisting of the separable sections K and B, and carrying all the operative parts, is insertable into and removable from the base T as a self-contained unit. As seen in Fig. 1, the opening in the base is sufficiently large to permit this insertion and removal of the unit K-B with 125 130

its contained parts. This unit, in the construction shown, is inserted as a whole into the top opening of the base until the flat annular flange 5 on the upper casing K contacts with the flat annular flange 6 which surrounds the opening in the base. This ready assemblage of the separate parts into an instrument ready for the market, facilitates the manufacturing of the loudspeaker 10 and thus lowers the cost thereof.

It will be understood that changes and modifications may be made in the various features of my invention without departing from the scope of the appended claims.

15 This application is a division of my co-pending case Serial Number 680,597, filed December 14, 1923.

What I claim as my invention is:

1. In a loud-speaking telephone receiver, an outer casing, a unitary support having electromagnetic acoustic mechanism mounted thereon, said support and mechanism constituting a unit insertable into and removable from said casing, a flange on said 20 casing, and a stand having an opening surrounded by a shoulder on which said flange is adapted to rest when said casing and support are inserted into the stand.

2. In a loudspeaker, a reproducer unit 30 comprising a housing member open at one end and having a sound passage at the other end for connection with an amplifier, a cap screwed into the open end of said member, a ring carried by said cap, a diaphragm supported on said ring, and electromagnetic mechanism mounted on said cap for operating said diaphragm, said cap and all parts carried thereby being insertable into and removable from said housing as a unit.

40 3. In a loudspeaker, a reproducer unit comprising a housing member open at one end and having a sound passage at the other end for connection with an amplifier, a one-piece casting removably secured to said housing, said casting comprising a disk screwed into the open end of said housing and a ring rigidly connected to said disk by spaced posts, a diaphragm supported on said ring, and electromagnetic mechanism mounted on 45 said disk for operating said diaphragm, said casting and all parts carried thereby being insertable into and removable from said housing as a unit.

45 4. A telephone loudspeaker comprising a base provided at the top with a central tubular aperture, a reproducer unit consisting of a housing in which electromagnetic operating mechanism is mounted, said housing having a cylindrical wall adapted to fit snugly into said aperture through the top thereof, and cooperating means on said base and said housing for limiting the inward telescoping movement of the housing on the base, said reproducer unit being removable as a whole 60 from the base through said aperture.

5. A telephone loudspeaker comprising a base provided at the top with a central tubular aperture, a reproducer unit consisting of a housing in which electromagnetic operating mechanism is mounted, said housing having a wall adapted to engage the wall of said aperture in a tight frictional joint as the housing is forced into the base, whereby said housing is rigidly supported on said base without the need of separate fastening means, said frictional joint permitting separation of housing and base.

6. A telephone loudspeaker comprising a base provided at its upper end with a cylindrical wall which defines a tubular aperture, 80 said wall terminating in a flat annular shoulder, a reproducer unit consisting of a housing containing electromagnetic acoustic mechanism, means on the upper portion of said housing for connecting the same with an amplifier, said housing having a cylindrical wall of slightly less diameter than said tubular aperture, so that said housing wall fits snugly into said aperture into engaging contact with the cylindrical wall of the base, and an annular flange on said housing arranged to engage said shoulder on the base for firmly supporting the reproducer unit on said base, said unit being removable from the base through said aperture

95 7. A telephone loudspeaker comprising a base having an outwardly flaring lower section and an upper section terminating in an opening surrounded by a flange or shoulder, a casing comprising a closed upper portion and an open lower portion, said upper portion extending above said base and said lower portion projecting through said opening in the base, a screw-threaded section on said lower portion, a neck extending from said upper portion, a horn mounted on said neck, a flange on said casing arranged to engage said base flange, so that said casing is firmly supported on said base, a cap having screw-threads arranged to engage the screw-threads on said casing, said cap and casing forming a housing which constitutes a unit insertable into and removable from said opening in the base, a magnet system supported within said housing, and an acoustic diaphragm in said housing and operatively connected with said magnet system.

100 8. In an electromagnetic sound reproducer, a reproducer unit having an upper casing member and a lower casing member separably connected by screw-threaded engagement, said members when assembled forming an enclosing housing with a cylindrical wall, electromagnetic operating mechanism carried by said lower casing member and removable therewith, an annular flange on said upper casing member, means on said upper member for supporting an acoustic horn, a supporting base provided at the top with a cylindrical extension projecting axially of the

base, said extension defining a tubular aperture into which the cylindrical wall of said housing is adapted to be inserted through the top of the base, the telescoping walls of said housing and said base engaging in a snug fit, and a shoulder on said base arranged to engage said flange on the casing for limiting the telescoping movement of said housing into said base, said housing being removable as a whole from the base through said tubular aperture.

9. An electromagnetic sound reproducer comprising a sound reproducer unit having a substantially cup shaped casing, an electromagnetic operating mechanism contained therein, a screw threaded cap engaging said casing having a flat annular flange substantially above the plane of the lower extremity of said casing, an acoustic horn supported in said cap, a supporting base having a flat central apertured portion of a size slightly greater than the diameter of said casing, a flat annular flange surrounding said apertured portion, a wall extending outwardly from said flange forming a continuation thereof and comprising said supporting base and means for securing said unit within said apertured portion by a vertically downward movement in which said flat annular flange

flange on said base forming a substantial support for said electromagnetic operating mechanism.

10. An electromagnetic sound reproducer including a sound reproducer unit comprising in combination a substantially cup shaped casing, an electromagnetic operating mechanism carried therein, a screw threaded cap engaging said casing and forming a flat annular flange substantially above the plane of the lower extremity of said casing, an acoustic horn supported in said cap, a supporting base having a diameter substantially larger than the diameter of said cap in the top thereof and having walls tapered to a diameter substantially larger than the diameter of said cap, a flat central apertured portion in the top of said base of a size slightly greater than the size of said casing and a flat annular flange formed integral with the wall of said base surrounding said apertured portion, and means for securing said unit within said apertured portion by a vertically downward movement in which said flat annular flange on said cap contacts with said flat annular flange on said base forming a substantial support for said electromagnetic operating mechanism.

ADOLPH A. THOMAS.
